UNITED STATES PATENT OFFICE

144,406

DESIGN FOR A CAMERA SUPPORT

Clarence S. McClellan, Santa Monica, Calif.

Application November 2, 1945, Serial No. 123,427

Term of patent 7 years

(Cl. D61—1)

To all whom it may concern:

Be it known that I, Clarence S. McClellan, a citizen of the United States, residing in Santa Monica, in the county of Los Angeles and State of California, have invented a new, original, and ornamental Design for a Camera Support, of which the following is a specification, reference being had to the accompanying drawing, forming part thereof, wherein:

Fig. 1 is a perspective view of a camera support showing my new design.

Fig. 2 is a side elevational view of said camera support.

Fig. 3 is a plan view of said camera support, and

Fig. 4 is an end view of said camera support.

I claim:

The ornamental design for a camera support, as shown.

CLARENCE S. McCLELLAN.
